Primary Examiner — Joseph Kukella*Assistant Examiner* — Darryl J Dardenne*(74) Attorney, Agent, or Firm* — Egbert, McDaniel & Swartz, PLLC(57) **CLAIM**

The ornamental design for an espresso machine, as shown and described.

DESCRIPTION

FIG. 1 is a front perspective view of an espresso machine showing our new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a rear perspective view thereof.

The broken lines shown FIG. 7 illustrate portions of the espresso machine that form no part of the claimed design.
